ACCUMULATIVE IMPACTING HEAD FOR NUT
RUNNERS AND THE LIKE

Norman E. Sims, Jr., Arlington, Va.

Application December 28, 1946, Serial No. 718,994

8 Claims. (Cl. 192—30.5)

1 This invention relates to improvements in nut runners and similar appliances.

In conventional nut runners a spring-loaded clutch is generally interposed between the tool spindle and the motor drive so that the clutch jaws remain in engagement, permitting the nut or screw to be turned through the torque of the motor until a critical point is reached, at which the resistance of the nut or screw overcomes the spring, causing intermittent slipping and re-engagement of the clutch, producing a series of impact blows between the clutch jaws, rotatively hammering the nut or screw to its final position of tightness.

Since in the conventional nut runner the clutch spring always releases at the same level of resistance, the impact blows are of substantially constant force. Furthermore, the motor must be powerful enough to develop a torque that will keep the nut or screw turning up to the point at which the clutch spring yields and the impact action starts.

One of the objects of the present invention is to provide a nut runner in which the clutch functions as such only to provide a "dead" tool spindle while the motor is running, to permit the tool to be applied to the nut, the clutch incorporating means for resolving the torque of the motor into a succession of rapid impact blows effective from the beginning of the nut running operation, the force of said blows being directly proportional to the resistance encountered, and therefore being slight at the beginning of the screwing movement and building up progressively to the magnitude required for the final tightening phase.

Another object of the invention is to provide a nut runner of the type described, in which each impact blow is the resultant of two force components, one being the torque of the driving means, and the other the reaction component of the immediately preceding impact blow.

A further object of the invention is to provide a nut runner in which the tool spindle carries a series of anvils and the driving means a rotor carrying a plurality of hammers engageable with said anvils for striking successive impact blows thereagainst to turn the spindle, with means for transferring the reaction component of each impact to the torque component of the next succeeding impact, whereby the blows of the hammers against the anvils are progressively augmented.

Other objects of the invention will appear as 55

the following description of a practical embodiment of the invention proceeds.

In the drawings which accompany and form a part of the specification, and throughout the several figures of which the same reference characters have been employed to denote identical parts:

Figure 1 is a longitudinal sectional view through a nut runner, incorporating the principles of the invention, the tool spindle being shown declutched from the drive;

Figure 2 is a side elevation of the rotary hammer carrier;

Figure 3 is a section taken along the line 3—3 of Figure 1;

Figure 4 is a diagrammatic view showing one of the hammers in striking position with respect to an anvil;

Figure 5 is a similar view showing the hammer 20 in recoil position;

Figure 6 is a view in end elevation of the hammer carrier, showing the parts in neutral position.

Referring now in detail to the several figures, the numeral 1 represents a casing preferably made in three parts, 2, 3 and 4, suitably secured together as by the bolts 5, with a partition plate 6, which functions as a bearing support, being between the parts 3 and 4 and clamped by said bolts. The casing part 2 contains a reversible electric motor, not shown, controlled by a switch 8, which is mounted on the outside of the casing. The part 3 houses a train of reduction gears 9, and is formed with a partition 10, constituting a bearing support, and the part 4 encloses the hammer and anvil mechanism 11, which embodies the concept of the present invention, said part 4 having a reduced end portion 12, which affords a housing and support for the yieldably mounted tool spindle 13. The latter, as shown, has a removable nut socket 12', which is exemplary of other tools with which the device is designed to operate.

The hammer mechanism comprises a rotatable carrier 14, including a shaft 15, and a diametrical plate 16 centered on said shaft at one end, the face of the plate 16 remote from the shaft having diametrically disposed projecting bearing bosses 17 and 18 on opposite sides of 50 the axial center of the plate 16, equidistant from said center and axially parallel to the axis of the shaft 15. Said shaft has extreme portions 19 and 20 journaled in bearings in the partition plate 6 and the partition 10, and an intermediate portion 21, which extends through the

final gear 22 of the reduction train and is secured thereto. The shafts 15 and spindle 13 are coaxial.

A pair of intermeshing gears 23 and 24, of the same size, are freely journaled on the respective bosses 17 and 18. These necessarily turn in reverse directions when rotated. Each carries on its outer face an arcuate hammer, the respective hammers being designated by the numerals 25 and 26. These have radial end faces, as shown, the hammers extending over an arc of one quadrant. The gears 23 and 24 are so meshed as to place the hammers in such phase relation that in one position of the gears the hammers are as shown in Figure 4, occupying opposite quadrants in the upper halves of the respective gears, with an end face of each coinciding with a line passing through the centers of the gears.

The tool spindle 13 is slidable in a bearing 21. At its inner end it is provided with a spider 28, preferably integral therewith, which carries at its ends the anvils 29, 30 and 31, spaced 120° apart. The anvils have radial end faces. The spindle 13 has an adjustable collar nut 32, screwed upon a threaded zone of said spindle and slidable within a counterbore in the reduced end of the casing, there being a spring 33 within said counterbore confined under compression between said collar nut and the inner end of the counterbore, an end thrust bearing intervening between said spring and collar nut. The effort of said spring is to bias the tool spindle 13 in an outward direction, keeping the anvils out of the path of rotation of the hammers so that the spindle is "dead," that is, not rotating. When the nut runner is pressed against the nut or screw, as the case may be, the spring 33 is compressed, causing the spindle to slide inward to bring the anvils 29, 30 and 31 into the plane of the hammers 25 and 26.

Provision is made to ensure that one of the hammers shall always be in outermost position in the path of the anvils when the motor is running free. With this end in view, one of the gears, for example, the gear 24 in Figure 6, is weighted with lead inserts 34, opposite the hammer 26, to counterbalance said hammer, neutralizing its centrifugal urge to move out in opposition to the weight of the hammer 25. Therefore, under the centrifugal force generated by the free rotation of the hammer carrier 14, the gears will always be in the relative positions shown in Figure 6, with the hammer 26 in outermost position, ready to strike a blow against an adjacent anvil in either direction, as soon as it is brought into the path of the anvils.

Referring now to the mode of operation of the nut runner, and assuming that the motor is running free with the hammer carrier 14 rotating in a counterclockwise direction, as indicated by the arrows *a* in the diagrammatic figures, and the gears and hammers being in the centrifugally determined position shown in Figure 6, and that the apparatus is under pressure so that the anvils are in the path of the hammer 25, this strikes a blow against the anvil 29. At the beginning of the nut screwing movement, the nut may oppose but little resistance to being turned, so that the anvil 29 yields readily to the hammer, the impact force being slight, not materially greater than that of the driving torque. But whatever the impact force may be, the reaction component against the hammer 25 causes said hammer to recoil in a clockwise direction, turning the gear 23

in a clockwise direction, imparting counterclockwise rotation to the gear 24 and the hammer 26 carried thereby. The hammers in the recoil position of the hammer 25 are shown in Figure 5.

In this Figure the gear 24 is bodily traveling counterclockwise, as indicated by arrow *a*, and the hammer 26 is traveling counterclockwise through the rotative impulses imparted to it by the recoil of the hammer 25, so the hammer 26 strikes the anvil 31 a blow, the force of which is the resultant of the torque force of the rotating hammer carrier augmented by the reaction force transferred from the hammer 25.

It will be understood from Figure 5 that the hammer 26 is shown at an intermediate position in its recoil movement, in which it is about to pass below the anvil 29, and that by the time the hammer 26 strikes the anvil 31, it will have moved completely out of the path of the anvil 29 and been carried thereunder by the counterclockwise translatory movement of the gear 23. The instant the hammer 26 strikes the anvil 31, it will recoil under the impact, reversing the direction of movement of the gears, so that the gear 23 now moves counterclockwise, driving the hammer 25 against the anvil 30, which hammer is already traveling towards said anvil under the constant circumferential torque of the rotating hammer carrier 14.

Since each impact component derived from the rotation of the hammer carrier is augmented by the reaction component derived from the immediately preceding impact, it follows that the blows progressively increase in intensity proportionately as the load resistance increases, and that they are at all times greater than would be the directly applied torque force. Consequently, a less powerful motor is adequate to carry a given load than if the torque force were directly applied to the load, or solely relied upon to produce impact blows through mere lost motion between the driving and driven parts.

The compound movement of the hammers relative to the anvils resultant from the translatory movement of the gears and the recoil movements of the hammers, through which compound movement each hammer strikes the anvils successively, passing beneath the anvil from which it rebounded, may be correctly described as an escapement action.

As shown and described, the hammers each circumscribe a 90° arc, and both have end faces in radial planes. This provides for actuation of the tool spindle in either direction. If the nut runner were designed solely for unidirectional operation, the hammers could be of less arcuate amplitude with only the leading ends, (the striking ends) being in radial planes.

While I have in the above description disclosed what I believe to be a practical embodiment of the invention, it will be understood by those skilled in the art that the particular application of the inventive principle to a nut runner, and the specific construction and arrangement of the parts, as shown, are to be regarded as illustrative and not to be construed as limiting the scope of the invention.

What I claim as my invention is:

1. Nut runner comprising a tool spindle rotatably mounted, having a radially extended head at one end, a plurality of spaced anvils carried by said head adjacent the periphery thereof at equal radial distances symmetrically about the axis of said spindle and in a common diametrical plane, a motor driven plate rotatably mounted

coaxial of said spindle, a pair of intermeshing gears mounted on said plate freely rotatable about axes perpendicular thereto and equidistant from the axis of rotation of said plate on opposite sides of said axis, and hammers carried by said gears operating between said anvils in the path thereof for converting the torque of said driving means into a succession of impact blows circumferentially against said anvils for rotating said spindle, the impact recoil of one hammer being transferred through said gears to the other hammer to augment the torque-generated impact of said other hammer.

2. Nut runner comprising a tool spindle rotatably mounted, having a radially extended head at one end, a plurality of spaced anvils carried by said head adjacent the periphery thereof at equal radial distances symmetrically about the axis of said spindle and in a common diametrical plane, a motor driven plate rotatably mounted coaxial of said spindle, a pair of intermeshing gears mounted on said plate freely rotatable about axes perpendicular thereto and equidistant from the axis of rotation of said plate on opposite sides of said axis, and hammers carried by said gears projecting from the faces of the respective gears between said anvils and into the path thereof for converting the torque of said driving means into a succession of impact blows circumferentially against said anvils for rotating said spindle, the impact recoil of one hammer being transferred through said gears to the other hammer to augment the torque-generated impact of said other hammer.

3. Nut runner comprising a tool spindle rotatably mounted, having a radially extended head at one end, a plurality of spaced anvils carried by said head adjacent the periphery thereof at equal radial distances symmetrically about the axis of said spindle and in a common diametrical plane, a motor driven plate rotatably mounted coaxial of said spindle, a pair of intermeshing gears mounted on said plate freely rotatable about axes perpendicular thereto and equidistant from the axis of rotation of said plate on opposite sides of said axis, and hammers carried by said gears projecting from the faces of the respective gears between said anvils, into the path thereof, of less circumferential length than the space between said anvils, for converting the torque of said driving means into a succession of impact blows circumferentially against said anvils for rotating said spindle, the impact recoil of one hammer being transferred through said gears to the other hammer to augment the torque-generated impact of said other hammer.

4. Nut runner comprising a tool spindle rotatably mounted, having a radially extended head at one end, three spaced anvils carried by said head adjacent the periphery thereof at equal radial distances symmetrically about the axis of said spindle and in the same diametrical plane, a motor driven plate rotatably mounted coaxial of said spindle, a pair of intermeshing gears mounted on said plate freely rotatable about axes perpendicular thereto and equidistant from the axis of rotation of said plate on opposite sides of said axis, and a hammer carried by each gear, said hammers operating between said anvils in the path thereof and being of less circumferential length than the space between said anvils for converting the torque of said driving means into a succession of impact blows circumferentially against said anvils for rotating said spindle, the impact recoil of one hammer being transferred

through said gears to the other hammer to augment the torque-generated impact of said other hammer, said hammers being arranged in such relative phase that when one is at the maximum distance from the axis of rotation of said plate, the other is at the minimum distance from said axis, whereby through the compound movement produced by the rotation torque of said plate and the recoil-produced movement of said hammers, each strikes successive anvils, escaping beneath the anvil last struck.

5. Nut runner comprising a tool spindle rotatably mounted, having a radially extended head at one end, a plurality of spaced anvils carried by said head adjacent the periphery thereof at equal radial distances symmetrically about the axis of said spindle and in a common diametrical plane, means for rotating said spindle comprising a motor driven plate rotatably mounted coaxial of said spindle, a pair of intermeshing gears mounted on said plate freely rotatable about axes perpendicular thereto and equidistant from the axis of rotation of said plate on opposite sides of said axis, and hammers carried by said gears projecting toward said anvils and being of less circumferential length than the space between said anvils, spring means for normally biasing said tool spindle and driving means axially apart whereby said driving means can normally rotate independently of said spindle, said hammers being movable into the path of said anvils under axial pressure applied contra to said spring means, into driving relation to said spindle whereby the torque of said driving means is converted into a succession of impact blows circumferentially against said anvils, the impact recoil of one hammer being transferred through said gears to the other hammer to augment the torque-generated impact of said other hammer.

6. Nut runner comprising a tool spindle rotatably mounted, having a radially extended head at one end, three spaced anvils carried by said head adjacent the periphery thereof at equal radial distances symmetrically about the axis of said spindle in the same diametrical plane, means for rotating said spindle comprising a motor driven plate rotatably mounted coaxial of said spindle, a pair of intermeshing gears mounted on said plate freely rotatable about axes perpendicular thereto and equidistant from the axis of rotation of said plate on opposite sides of said axis, and hammers carried by said gears projecting toward said anvils and being of less circumferential length than the space between said anvils, spring means for normally biasing said tool spindle and driving means axially apart whereby said driving means can normally rotate independently of said spindle, said hammers being movable into the path of said anvils under axial pressure applied contra to said spring means whereby the torque of said driving means is converted into a succession of impact blows circumferentially against said anvils, the impact recoil of one hammer being transferred through said gears to the other hammer, to augment the torque-generated impact of said other hammer, said hammers being arranged in such relative phase that when one is at the maximum distance from the axis of rotation of said plate, the other is at the minimum distance from said axis, whereby through the compound movement produced by the rotation torque of said plate and the recoil-produced movement of said hammers, each strikes successive anvils, escaping beneath the anvil last struck.

7. Nut runner comprising a tool spindle rotatably mounted, having anvil means at one end radially offset from the axis of rotation, a motor drive for said spindle comprising a motor driven plate rotatably mounted coaxial of said spindle, a pair of intermeshing gears mounted on said plate freely rotatable about axes parallel to the common axis of rotation of said spindle and plate, equidistant from said axis on opposite sides thereof, a hammer projecting from each gear toward said anvil means, said hammers being arranged in such relative phase that when one is at the maximum distance from the axis of rotation of said plate the other is at the minimum distance, the radius of rotation of said hammers when at said maximum distance being equal to the radius of rotation of said anvil means, spring means normally biasing said anvil means and motor driven plate axially apart whereby said plate can normally rotate independently of said spindle, said hammers being movable into the zone of said anvil means under axial pressure applied contra to said spring means, one of said gears being provided with means for counterbalancing the weight of the hammer of that gear, nullifying the centrifugal moment of that hammer whereby the unbalanced weight of the other hammer causes it to assume and maintain a position at maximum distance from the axis of rotation of said plate when said plate is running free, in position to strike said anvil means when in the zone of said means, in either direction of rotation of said plate.

8. Escapement means comprising a rotor includ-

ing a pair of intermeshing gears freely rotatable about axes parallel to the axis of rotation of said rotor and equidistant from said axis on opposite sides thereof, spaced anvils, means supporting said anvils, maintaining them at equal radial distances symmetrically about the produced axis of said rotor and in a common diametrical plane, a hammer projecting from each gear into the zone of said anvils, said hammers being of less circumferential extent than the space between said anvils and being arranged in such relative phase that when one is at the maximum distance from the axis of rotation of said rotor the other is at the minimum distance from said axis, said maximum distance being equal to the radial distance of said anvils from said produced axis, whereby through the compound movement of said hammers produced by the rotation torque of said rotor and the recoil-produced movement of said hammers, each strikes successive anvils, escaping beneath the anvil last struck.
